DESIGN FOR A KILTIE TONGUE FOR A SHOE

George A. Gleason, Reading, Pa.

Application September 18, 1935, Serial No. 58,613

Term of patent 3½ years

To all whom it may concern:

Be it known that I, George A. Gleason, a citizen of the United States of America, residing in Reading, county of Berks, and State of Pennsylvania, have invented a new, original, and ornamental Design for a Kiltie Tongue for a Shoe, of which the following is a specification, reference being had to the accompanying drawing, forming part thereof.

I claim:

The ornamental design for a kiltie tongue for a shoe as shown.

GEORGE A. GLEASON.
